UPHOLSTERY STRUCTURE

Jack C. Gordon, Detroit, Mich., assignor to Allen Industries, Inc., Detroit, Mich., a corporation of Delaware

Original application March 6, 1939, Serial No. 280,245. Divided and this application March 18, 1940, Serial No. 324,693

4 Claims. (Cl. 155—198)

This invention relates generally to upholstery units such as arm rests for vehicle bodies and the like, and constitutes a division of my application filed March 6, 1939, bearing Serial No. 280,245.

One of the essential objects of the invention is to provide a unit of this type that may be made from relatively low cost material but that has the valuable and advantageous characteristics of more expensive structures such as those formed from sponge or molded rubber.

Another object is to provide a unit that has enhanced resiliency and a strong tendency to resume its original shape after deflection.

Another object is to provide a unit that is completely enveloped by a skin of latex or the like and that may, if desired, be reenforced by an open mesh fabric or other suitable material.

Other objects, advantages and novel details of construction of this invention will be made more apparent as this description proceeds, especially when considered in connection with the accompanying drawing, wherein:

Figure 1 is a perspective view of an upholstery unit embodying my invention;

Figure 2 is an edge elevation of two plies of fibrous material which form the body portion of the unit;

Figure 3 is a top plan view of the structure shown in Figure 2;

Figure 4 is a view similar to Figure 2 but showing the structure after an end portion of the lowermost layer has been return-bent;

Figure 5 is a sectional view through the three-ply end portion of the assembly after the reenforcing fabric has been applied to the upper surface thereof;

Figure 6 is a vertical sectional view through the unit after it has been applied to a rigid support or frame member and showing the fabric covering applied thereto.

Referring now to the drawing, A is the body, B is the skin coating of latex, and C is the fabric covering of an upholstery unit embodying my invention.

As shown, the body A is elongated in form and comprises two layers 10 and 11 of fibrous material such as cotton batting. Preferably the lower layer 11 is longer than the upper layer 10 and has an end portion 12 return-bent against the lower surface of the upper layer so that the bend 13 is short of the adjacent end 14 of the upper layer. The opposite ends 15 and 16 of the layers are substantially flush with each other.

A skin coating B of latex completely envelopes 55

the body A and serves as a tie between the layers 10 and 11 at the edges thereof to bond the parts firmly together.

The fabric covering C is preferably an open mesh strip of suitable material such as tobacco cloth that adheres to the latex-coated upper surface of the upper layer 10.

In the process of construction, the layers 10 and 11 are preferably die cut from suitable sheets of cotton batting. If desired, either or both layers 10 and 11 may be coated with latex before being assembled. When the lower layer 11 is assembled with the upper layer 10, the end portion 12 of the lower layer is bent back so as to lie flat against the underside of the upper layer and against the upper side of the lower layer. Thus, there are three plies at one end of the structure with the end portion 17 of the uppermost ply projecting endwise beyond the two lower plies. 20 The assembly is then coated with latex so that all exposed surfaces and edges thereof are covered. If desired, such coatings of latex may be subjected to warm air or heat in a suitable oven (not shown) to expel moisture and to at least partially cure the latex. In fact, the assembly is provided with an uninterrupted or continuous skin coating that constitutes an envelope therefor. The assembly may then be reinforced by the fabric C which is preferably equal in area to the upper surface of the upper layer 10. This fabric is bonded to the assembly by the latex coating B.

When the assembly is placed on a rigid support or frame member such as D of a vehicle body, the three-ply end thereof is bent over the forward edge 18 of said support and is preferably drawn downwardly against the depending portion 19 of the support, as illustrated in Figure 6. A suitable covering E of fabric is then applied to the assembly and suitably anchored to the support D to hold the assembly in place. Where it is necessary the body A may be cut away at 25 before being enveloped with latex to accommodate any upstanding shoulder or projection (not shown) of the support D.

45 Thus, from the foregoing it will be apparent that the upholstery unit is a self-contained resilient cushion. Inasmuch as the skin coating B is applied after the fibrous body A is fashioned, it will take the shape of the contour thereof and will hold this contour against permanent distortion.

What I claim as my invention is:

1. A self-contained arm rest unit having two preformed superposed elongated layers of unimregnated fibrous material, the width of said

layers being substantially equal, one of said layers having an endwise extension return-bent between said layers at one end thereof and providing a three-ply structure for a portion of their length, an exposed surface of the other layer having a coating of latex and a reinforcing fabric adhering in surface-to-surface relation thereto, the other exposed surfaces of the layers being coated with latex, the latex at the edges of the layers serving to bond such layers together.

2. A self-contained arm rest unit having an elongated fluffy laminated body and an uninterrupted resilient covering therefor, the upper lamina of the body being substantially straight throughout its length, the lower lamina of the body being straight from one end thereof to a point substantially midway its ends and having its other end return-bent upon itself and bearing in surface-to-surface relation against the underside of the upper lamina, and the covering being a sticky adhesive substance tenaciously adhering to the fibrous material on all exterior surfaces of the body, the adhering covering at the edges of the body serving to tie flexibly to-

gether the fibrous material of adjacent laminae including the return-bent portion aforesaid.

3. A self-contained arm rest unit having two preformed superposed elongated layers of un-impregnated fibrous material, one of said layers being longer than the other and having an end portion thereof return-bent between said layers and providing a three-ply structure adjacent one end of the unit, the exposed surfaces of the layers being completely coated with latex, the latex at the edges of the layers serving to bond such layers together.

4. A self-contained arm rest unit having an elongated fluffy laminated body provided with an uninterrupted adhering covering, one lamina of the body having an end portion thereof return-bent upon itself and bearing in surface-to-surface relation against the adjacent lamina intermediate the ends thereof, whereby a portion of said adjacent lamina projects endwise beyond said return-bend, the adhering covering at the edges of the body serving to tie flexibly together the fibrous material of adjacent laminae including the return-bent portion aforesaid.

JACK C. GORDON.
